TUNING INDICATOR DEVICE

Arnold T. Vossen, Eindhoven, Netherlands, assignor to Radio Corporation of America, a corporation of Delaware

Application February 29, 1940, Serial No. 321,412
In the Netherlands July 29, 1939

3 Claims. (Cl. 250—40)

This invention relates to a wireless receiving set comprising a coarse and a fine adjustment tuning device, the latter permitting of spreading wave bands. This so-called band spreading is primarily used in the short-wave region in which the stations are assembled in a number of wave bands and in which the stations comprised in the same band are closely adjacent each other on the tuning dial. Generally, the same tuning member as that by means of which the long and medium wave ranges are attended also serves to cover the short-wave range but in this latter range due to the stations being in close proximity to each other it is very difficult to tune to any station comprised in any of the bands by means of this tuning member which as regards this range is of coarse adjustment. Now, by using band spreading, that is to say by passing over from the coarse adjustment tuning device to a fine adjustment tuning device, it is nevertheless possible to tune the set readily and to a sufficiently accurate extent to the short wave stations. According to a well known method of band spreading a small variable condenser is connected in parallel with each of the tuning circuits. As an alternative, band spreading may be obtained by means of a variable inductance included in each of the tuning circuits. In the said cases the coarse adjustment tuning device may be constituted either by a tuning condenser or by a variable inductance.

In order that it may be possible to tune the set by means of the fine adjustment tuning device to a station comprised in any of the wave bands to be spread it is therefore sufficient to tune in to the proximity of the station by means of the coarse adjustment tuning device, after which accurate tuning to the station can be attained by means of the fine adjustment tuning device. Since for the purpose of tuning to a short wave station the user of the wireless receiving set generally disposes of a tuning dial associated with the fine adjustment tuning device it is essential in order to enable continuous use of this dial that the adjustment of the fine adjustment tuning device should always be identical whenever tuning is effected to the said station. This means that in this case it is also necessary that the coarse adjustment tuning device should always effect the same adjustment when the set is being tuned to the same station. This also applies to the other stations comprised in the various wave bands. It is customary to choose the adjustment of the coarse adjustment tuning device for each of the short wave stations so as to coincide with the

center of the wave band associated with each of these stations.

Now, the invention has for its object to provide a device enabling the user of the wireless receiving set to effect accurate tuning to a given point in a wave band, for example, to the center of the wave band, by means of the coarse adjustment tuning device. A wireless receiving set according to the invention is characterized in that the attainment of that given point in a wave band in which tuning to a given wave length has to be effected by means of the fine adjustment tuning device is made known by a signalling device operating e. g., by optical means.

15 In one embodiment of the invention the movable part of the coarse adjustment tuning device has coupled to it one or more contacts adapted to cooperate with one or more contacts arranged in the set in a stationary manner, the arrangement being such that upon attainment of a given point, e. g., the center of a wave band capable of being spread by means of the fine adjustment tuning device, an electrical circuit is opened or closed so that the signalling device is set into operation. As mentioned before, the coarse adjustment tuning device may be constituted either by a variable inductance or by a condenser. According to the invention, when use is made in the wireless receiving set of a variable condenser 20 which may be either a rotary condenser or a sliding-electrode condenser, the movable contacts may be coupled to the shaft of the condenser.

According to the invention, the wireless receiving set may be constructed in various ways. In 25 one embodiment of the invention one contact for each wave band is arranged so as to be stationary relatively to the shaft of the coarse adjustment tuning device, said contact cooperating with a single contact arranged in the set in a stationary manner. It is, however, also possible for the contacts associated with the wave bands to be arranged in the set in a stationary manner and to cause them to cooperate with one contact arranged in a stationary manner in relation to the 30 shaft of the coarse adjustment tuning device.

In a further embodiment of the invention the contacts cooperating with each other may be constituted by a pair of contacts on the one hand and a single contact on the other hand. The 35 nature of the cooperation depends on the construction and the arrangement of the said contacts. The construction and the arrangement may be such, for example, that when the coarse adjustment tuning device is tuned to the center of a wave band the two contacts of the pair of

contacts are shunted by the other single contact. The number of pairs of contacts may be equal to the number of wave bands in which band spreading is used. They may be arranged in the set in a stationary manner and in this case they may cooperate with a single contact coupled to the movable part of the coarse adjustment tuning device; alternately, they may, however, be coupled to the movable part of the tuning member and in this case they are adapted to cooperate with the contact arranged in the set in a stationary manner. It is also possible to provide a single contact for each wave band to be spread, the contacts being in this case adapted to cooperate with one pair of contacts. In this case, the pair of contacts may, as before, be coupled similarly to the method hereinbefore described for the pairs of contacts, to the movable part of the tuning member or they may be arranged in the set in a stationary manner. The same remark applies to the contacts cooperating with the pair of contacts.

According to the invention, when the wireless receiving set is furnished with a rotary condenser that acts as the coarse adjustment tuning device the shaft of the rotary condenser may carry a disc or drum which, on its periphery, carries a pair of contacts for each of the wave bands to be spread, a contact arranged in the set in a stationary manner bearing on the periphery of the disc or drum, the arrangement being such that when the condenser is tuned, for example, to the center of a wave band the contacts of the pair of contacts associated with this wave band are shunted by the contact arranged in the set in a stationary manner.

A suitable optical signalling device may be obtained by means of one or more sources of illumination. The signal which is given upon attainment of a given point in a wave band may be the sudden illumination or the extinguishment of an incandescent lamp, the simultaneous operation of two lamps, other possibilities being not precluded.

According to the invention, in the last discussed form of construction of a wireless receiving set according to the invention, in which consequently a disc or drum carries pairs of contacts equal in number to the number of wave bands to be spread and capable of cooperating successively with a contact arranged in the set in a stationary manner, the signalling device may be constructed as follows. If the contact arranged in the set in a stationary manner is only connected to one of the contacts of a pair of contacts, an electrical circuit is closed which includes a source of illumination giving off a given color, and if the contact arranged in the set in a stationary manner is only connected to the other contact of the pair of contacts a circuit is closed which includes a source of illumination emitting the complementary color of the color of the first-mentioned source of light, whereas in the case of the pair of contacts being shunted by the contact arranged in the set in a stationary manner both circuits are closed. If one of the sources of light gives off, for example, red light and the other source of illumination green light, both sources of light will give off light in the case of both contacts of a pair of contacts being shunted by the contact arranged in the set in a stationary manner. If the light of both sources of illumination is thrown on to a screen this will be illuminated white.

In one preferred embodiment of the wireless

receiving set according to the invention a contact cooperating with a pair of contacts and adapted to move relatively thereto cooperates when the coarse adjustment tuning device has arrived at one end of a wave band, with one of the ends, remote from each other, of the contacts of this pair of contacts. In the embodiment described hereinbefore one of the sources of light, for example the red one, will operate upon a wave band being entered into, whereas this source of illumination extinguishes on the wave band being left on the same side. The entering into or leaving of the wave band on the other side results in the other source of illumination, in this instance consequently the green one, starting to operate or extinguishing respectively.

In order that the invention may be clearly understood and readily carried into effect it will now be described more fully with reference to the accompanying drawing, in which

Fig. 1 shows two tuning dials of the wireless receiving set comprising a coarse and a fine adjustment tuning device.

Fig. 2 shows a tuning circuit of the wireless receiving set.

Figs. 3 and 4 show two different positions of the condenser shaft which has coupled to it a number of pairs of contacts adapted to cooperate with a contact arranged in the set in a stationary manner.

Fig. 5 diagrammatically shows the contact device and the signalling device attended thereby.

Figs. 6A, B, C and D show various positions of the contact arranged in the set in a stationary manner relatively to a pair of contacts coupled to the condenser shaft.

Fig. 7 diagrammatically shows a part of the signalling device.

The tuning dial 1 shown in Fig. 1 comprises five wave bands, viz. the 14 meter, 16 meter, 20 meter, 25 meter and the 30 meter bands. A number of stations, say 20, are assembled in each of these bands. By reason of the compact arrangement of the stations on the tuning dial it is very difficult to tune to a station comprised in any of the wave bands in a manner similar to that adopted in the medium or long wave band. This difficulty is solved by the use of band spreading. One manner of band spreading is illustrated in Fig. 2. In this figure one of the tuning circuits of the wireless receiving set is shown to be built up from an inductance L, a variable condenser C, which generally also serves for tuning in the medium and long wave bands, and a condenser C' which is connected in parallel with this condenser and is small compared therewith. The condenser C permits of covering the entire tuning dial 1, and the condenser C' of covering only a small part, but with substantially greater accuracy since in the case of equal deviations of the movable parts of the condensers the condenser C' submits the tuning circuit to a substantially smaller variation in capacity than in the case of the condenser C. Thus a tuning dial may be provided for each wave band which is substantially larger than the wave band. Such a tuning dial is shown in Fig. 1 for the 30 meter band and designated by 2. The other spread wave bands may also be arranged on this dial but it is also possible to use a separate tuning dial for each spread wave band. In tuning to a given station lying, for example, in the 30 meter band the following process is adopted. By means of the tuning condenser C the set is tuned to

the wave band that contains the desired station. Since the tuning dial 2 is rated at a given tuning of the condenser C in the wave band it is necessary for enabling the tuning dial 2 to be used that the condenser C should be retuned accurately to the same point in the wave band. Generally, the center of the wave band is taken for such point. Next, by means of the fine adjustment condenser C' the set can be tuned to the desired station which is indicated on the tuning dial 2. If, however, the condenser C were tuned slightly to the side of the correct tuning position in the wave band, the desired station, if it can be received at all, will not longer coincide with the indication on the tuning dial 2.

According to the invention, in order to enable the user of the wireless receiving set to tune the coarse adjustment tuning device, that is to say the condenser C in the case discussed here, correctly in an easy and accurate manner, provision is made of a signalling device one form of construction of which will be set out by reference to the Figs. 3, 4, 5, 6 and 7.

The shaft 3 (Figs. 3 and 4) of the rotary condenser, which is constructed as a coarse adjustment tuning device, has fast on it an insulating disc 4 carrying at its periphery five pairs of contacts each comprising the contacts *a* and *b*. These pairs of contacts are designated by 14*m*, 16*m*, 20*m*, 25*m* and 30*m*. A contact 5 constructed as a roller supported in the carrier 6 is mounted in the set in a stationary manner. This roller is forced into contact with the periphery of the disc 4 by a compression spring 7. The pairs of contacts 14, 16, 20, 25 and 30 are distributed in such manner along the circumference of the disc 4 that when they cooperate with the contact roller 5 the set is tuned in the 14 meter, 16 meter, 20 meter, 25 meter and 30 meter bands respectively. The contacts *a* and *b* of each pair of contacts constitute the limbs of a V which in this form of construction form a very obtuse angle with each other. In Fig. 6 several positions of the contact roller 5 relative to the disc and one pair of contacts *a*, *b* are shown diagrammatically, said positions being successively obtained when in Fig. 3 the condenser shaft 3 is rotated in the direction shown by the arrow. In Fig. 6A and also in Fig. 3 the roller 5 bears on the circumference of the disc 4. In Fig. 6B the roller 5 has engaged the contact *b*. In Fig. 6C, similarly to Fig. 4, the roller 5 is connected to both contacts *a* and *b*, whereas in Fig. 6D the roller 5 engages with the contact *a* alone.

For each pair of contacts it is, therefore, possible to indicate the position in which both contacts *a*, *b* contact with the roller 5. Since this is a sharply bounded position this is taken advantage of to make known the attainment of e. g. the center of the wave band associated with the pair of contacts.

Fig. 5 diagrammatically shows the contact device *a*, *b*, 5 and the signalling device attended thereby. The signalling device comprises two sources of illumination 6 and 7 of which the source of illumination 6 can give off red light, and the other source of light 7 can give off a complementary color, i. e., green light. The source of light 6 is connected to one end of the secondary 8 of the transformer and to the *a* contact of the pairs of contacts. The source of light 7 is connected to the other end of the winding 8 and to the *b* contact of the pairs of contacts. The contact roller 5 is connected to the center of the winding 8. Now, when the contact

roller 5 is connected to the *2a* contact alone, only the electric circuit which includes the source of light 6 is closed. This source of light thus radiates red light. If the contact roller 5 contacts with the *b* contact alone, only the circuit for the source of light 7 is closed. This is consequently made known by radiation of green light. If the center of a wave band is reached the contact roller 5 engages with both contacts *a*, *b* with the result that the circuits of both lamps are closed and consequently both red and green light are radiated. If as shown in Fig. 7 the two sources of illumination 6 and 7 are arranged at the back of a ground glass 9, this glass will appear illuminated white on the front side. If tuning is effected by means of the coarse adjustment tuning condenser C but slightly by the side of the center of the wave band either the source of light 6 (red) or the source of light 7 (green) will burn. Thus, the user has got an accurate indication when the position of the coarse adjustment tuning device must occupy to pass over to band spreading by means of the fine adjustment tuning device, is reached. Those skilled in the art are fully aware of the manner of connecting each pair of contacts *a*—*b* into parallel with light sources 6 and 7 so that as the disc 4 rotates roller 5 will successively close the signal circuits as explained in connection with Fig. 5.

In addition, according to the invention on entering into a wave band or leaving it by means of the coarse adjustment tuning device the user of the set may also obtain an indication. In the form of construction shown in Fig. 3 et seq., the *a* and *b* contacts of each pair of contacts are constructed for this purpose in such manner that when the tuning condenser C is tuned to one or to the other of the ends of a wave band, for example the 30 meter wave band, the contact roller 5 engages the end *a'* or the end *b'*, shown in Fig. 3, of the contacts *a* and *b* of the pair of contacts 30. In this case either the red source of light 6 or the green source of light 7 will, therefore, burn. At the moment when the wave band is left on one or on the other side the contact roller 5 will therefore also leave the *a* contact at the end *a'* or the *b* contact at the end *b'* so that the source of light 6 or 7 respectively extinguishes.

What I claim is:

1. In a multi-band receiver of the type having a main reactor which is continuously variable for tuning the receiver through at least a plurality of high frequency bands and which is adjustable to a single predetermined position in each of said high frequency bands, said positions being different for said several bands, and an auxiliary reactor continuously variable to tune the receiver through each of said high frequency bands and for effecting band spread in each band, means for effecting substantially accurate adjustment of the main reactor to said predetermined positions and for visually indicating the same, comprising a member movable with the main reactor, a plurality of pairs of closely spaced contacts, one pair for each predetermined position, carried by said member, said contact pairs being spaced apart in the same angular relation as the predetermined positions of the main reactor, a normally open circuit including a visual indicator individually connected to each contact of said pairs, and a fixed contact disposed in the path of the movable contacts adapted upon varying the main reactor to successively close first one, then both and finally the other of each

of said normally open pairs of circuits whereby the accurate adjustment and the position of the tuning reactor on either side thereof are visually indicated.

2. In a radio receiving apparatus, a tuning reactor and a control shaft therefor, manually operated means for actuating said shaft, and means to effect accurate adjustment of said reactor to a desired position and to visually indicate said accurate adjustment and also positions adjacent thereto, said means comprising a member in the form of a disc movable with the control shaft, a pair of spaced contacts carried in a peripheral depression of the disc member, a normally open circuit including a light source individually connected to each of said contacts, and a relatively fixed contact roller constructed and arranged to ride on the disc periphery upon operation of the control shaft to successively close first one, then both and finally the other of said normally open circuits whereby the accurate adjustment and the position of the tuning reactor on either side thereof are visually indicated.

3. A multi-band radio receiver capable of re-

ception in at least a plurality of high frequency bands, comprising, at least one tunable circuit including a coarse adjustment variable condenser for continuously tuning said circuit over said 5 several bands, means for adjusting said tuning condenser to the mid-frequency of each high frequency band, a fine adjustment variable condenser included in said circuit and adjustable when the coarse adjustment condenser is ad-10 justed to one of the mid-frequency positions to effect band spreading of said tunable circuit to tune the same over the corresponding high frequency band, and means cooperatively related with the adjusting means for the coarse adjust-15 ment condenser for giving a visual indication upon adjustment of said condenser to its mid-frequency position, said means comprising a fixed contact, a pair of contacts movable with the coarse adjustment condenser and so disposed 20 that they come into contacting relation with the fixed contact only upon adjustment of said condenser to its mid-frequency position, and a pair of circuits each including a light source adapted to be energized at said position of adjustment.

ARNOLD T. VOSSEN.
